SEWING MACHINE CABINETS
Stefan Schaerf, Old Chum Creek Road, Healesville,
Victoria, Australia
Filed Jan. 14, 1963, Ser. No. 251,223
3 Claims. (Cl. 312—30)

This invention relates to a sewing machine cabinet of the type comprising a box, having the head of the machine pivotally connected to the box for movement from a secluded position within the box to an operative position supported upon, and projecting from the top of the box.

In known cabinets of this type it is customary for the top thereof to comprise a hinged portion, and a fixed portion which together define an aperture through which the head is raised and lowered. The hinged portion is raised to permit movement of the head between the operative and inoperative position and lowered to support the head in the operative position. A separate hinged lid is also provided to cover the apertured top when the head of the machine is in the inoperative position so that an uninterrupted flat top surface is presented.

Although this cabinet is satisfactory in use, it is expensive to manufacture both from the aspect of material and labour due to the double top construction.

It is therefore the principal object of the present invention to provide a sewing machine cabinet of the type herein specified which is relatively inexpensive to manufacture, effective in operation, and of pleasing appearance and finish.

With the above stated principal object in view there is provided according to the present invention a sewing machine cabinet of the type herein specified having a closure member comprising two sections shaped and arranged to interfit in one assembled position to present an uninterrupted surface, and separable for relative rearrangement to define an opening through which the head of the machine projects to be supported in an upright operative position by said two sections of the closure member.

More specifically there is provided a sewing machine cabinet of the type herein specified having a two section closure member constituting the major portion of the top of the cabinet, said two sections of the closure member being separable and shaped and arranged so as to interfit in one assembled position to present an uninterrupted closure and in another to define an opening through which the head of the machine projects to be supported in an upright operative position by said two sections of the closure member.

Conveniently the two sectioned closure is slidably mounted in the cabinet so that each section can be slid longitudinally relative to the cabinet. Each section of the closure member is L or step shaped at one end and the projecting sections of these stepped ends interfit in assembly to form an uninterrupted flat surface when the machine head is located in the inoperative position within the cabinet.

When it is desired to use the machine one section of the closure member is removed from the cabinet, turned over, and reassembled in the cabinet so that the projecting sections of each stepped end are in abutting alignment, and thereby form an aperture through which the head of the machine projects.

The invention will be more readily understood from the following description of one practical arrangement of the sewing machine cabinet as illustrated in the accompanying drawings.

In the drawings:

FIGURE 1 is a perspective view of the closed cabinet from above.

FIGURE 2 is a perspective view of the cabinet from below.

FIGURE 3 is a view similar to FIGURE 1 with the

2

cabinet closure in the open position to support the machine head.

FIGURE 4 is a plan view of the cabinet with the closure removed.

FIGURE 5 is a sectional view along line 5—5 of FIGURE 4.

Referring now to FIGURE 1 the cabinet comprises a box 6 of sufficient depth to house the machine head, supported on four legs 7 each inclined outwardly at its lower end. The legs 7 are screwed into sockets 8 fitted to the underside 9 of the box 6 so that they may be removed to facilitate transportation of the cabinet.

The top of the box has a marginal rail 10 on one side to which the head of the machine is pivotally connected by conventional hinges 11. A groove 12 is provided along the inner vertical edge of the rail 10 and a similar groove 11a is provided on the opposite side wall 13 of the box to form tracks for the closure member 14. The groove in the wall 13 is visible in FIGURE 5.

FIGURE 20 The closure member 14 comprises two flat sections 15 and 16 each having a thickness at its longitudinal edges to fit into the respective grooves 11a and 12. Each closure section has one end shaped in the form of a step defined by two parallel transverse edges 19 and 19a extending across half the width of the section, and a longitudinal edge 20 of a length equal to half the length of the aperture required for the machine head to project through.

When the two sections 15 and 16 are assembled in the grooves 11a and 12 so that the respective stepped ends interfit as shown in FIGURE 1 they form a complete closure for the cabinet, and when assembled with the projecting portions 21 and 21a of the stepped ends abutting they form the rectangular aperture 22 through which the head 24 of the machine projects. The projections 21 and 21a are dimensioned so that the length and width of the aperture 22 is less than the corresponding dimensions on the base of the head 24 so that in the projected operating position the head is supported on the marginal portion of the two sections surrounding the aperture, as shown in FIGURE 3.

With the two sections assembled to define the aperture 22 they have an overall length greater than that of the cabinet, and this additional length provides a work table 25 to support the material being sewn, as shown in FIGURE 3.

The interior of the box 6 has three compartments, 28, 29 and 30 bounding the space 31 occupied by the machine head when it is in the inoperative position. The inner walls 32 and 33 of these compartments extend to contact the under face of the closure sections 15 and 16 and provide additional support when the machine head is resting thereon. Preferably the compartment 28 is of such dimensions that the legs 7 can be placed therein in when removed for transporting the machine.

A handle 35 may also be provided on one side of the box to facilitate carrying.

I claim:

1. A sewing machine cabinet of the type herein specified having a two section closure constituting the major portion of the top of the cabinet and mounted in a common horizontal plane for sliding movement in a longitudinal direction relative to each other and to the cabinet, each section being step shaped at one end so that in one assembled position of the sections the step shaped ends interfit to present an uninterrupted closure and upon inverting one of the sections the projections formed by the step shaped ends are in abutting alignment to define an opening through which the head of the machine projects to be supported in an upright operative position upon said two sections.

2. A sewing machine cabinet of the type herein specified having a closure member comprising two sections shaped and arranged to interfit in one assembled position to present an uninterrupted surface, and separable for relative rearrangement to define an opening through which the head of the machine projects to be supported in an upright operative position by said two sections of the closure member, each section of the closure member being step shaped at one end so that in one assembled position of the sections the step shaped ends interfit to present the uninterrupted closure, and upon inverting one of said sections the projections formed by the step shaped ends are in abutting alignment to define the opening.

3. A sewing machine cabinet of the type herein specified having a two-section closure member constituting the major portion of the top of the cabinet, said two sections of the closure member being separable and shaped and arranged so as to interfit in one assembled position to present an uninterrupted closure and in another to define an opening through which the head of the machine projects to be supported in an upright operative position by said two sections of the closure member, each section

of the closure member being step shaped at one end so that in one assembled position of the sections the step shaped ends interfit to present the uninterrupted closure, and upon inverting one of said sections the projections formed by the step shaped ends are in abutting alignment to define the opening.
